UNITED STATES PATENT OFFICE

172,294

HOUSING FOR A CARDIAC INDICATOR

Karl McCormick, Houston, Tex., assignor to
W. F. Wilson, Houston, Tex.

Application June 29, 1953, Serial No. 25,703

Term of patent 14 years

(Cl. D52—1)

To all whom it may concern:

Be it known that I, Karl McCormick, a citizen of the United States, residing at Houston, in the county of Harris, State of Texas, have invented a new, original, and ornamental Design for a Housing for a Cardiac Indicator, of which the following is a specification, reference being had to the accompanying drawing, forming a part hereof.

Fig. 1 is a perspective view of a housing for a

cardiac indicator, embodying my new design; and
Fig. 2 is a top plan view thereof.

What is claimed is:

The ornamental design for a housing for a cardiac indicator, substantially as shown.
